BOOKBINDING

Frank H. Crump, Los Angeles, Calif.

Application June 13, 1934, Serial No. 730,369

7 Claims. (Cl. 281—25)

This invention relates to improvements in binders, and more particularly to binders of that type in which the leaves are built upon tubular posts secured through cover plates as disclosed in U. S. Patent 1,093,835 of April 21, 1914 granted to Frank H. Crump, and its objects are as follows:—

First, to provide one of the covers (the bottom cover) with "floating" tubular posts so-called because of their being initially stopped short of being completely driven home into engagement with screw nails which afterwards rigidly secure them to the bottom cover, the floating action of the top of the posts which have previously been cut off above the top cover ceasing when unshouldered screw nails are driven into the posts, the applied force driving the posts clear down to the shoulders of the screw nails in the bottom cover and so compressing and binding the pages in a fixed position between the covers.

Second, to provide compression means for permanently securing one end of a tubular post to the bottom cover plate of a binder and to utilize similar means for the permanent connection of the other end of the tubular post to the top cover plate whereby the cover plates are drawn closely together after severing one end of the tubular post at the required point above the top cover, the compression means concealing the tubular post ends in the top and bottom cover plates.

Third, to provide angular top and bottom cover plates on one side of which the tubular connecting posts are compressively secured, the other side of said plates forming a partial covering for the back edges of the sheets to be bound.

Fourth, to provide an independent back, of metal or other suitable material, held in position outside of the angular top and bottom cover plates by means connecting it with two or more of the tubular posts, the independent back concealing the exposed portion of the back edges of the leaves, the three-piece back automatically providing a covering for a variable quantity of sheets.

Fifth, to provide a binding which has a flexible back held in position inside of the angular top and bottom cover plates by carrying means secured to one or more of the tubular connecting posts and passing through the independent flexible back.

Sixth, to provide folded over angular metal top and bottom cover plates with reinforcing means in the folds of which the foregoing compression means in the ends of the tubular connecting posts are secured.

Seventh, to provide folded over metal top and bottom cover plates without the angle plate but with reinforcing means in the fold to which the foregoing compression means is secured as before.

In the drawings:—

Figure 1 is a perspective view of a completed and closed binder.

Figure 2 is a detail perspective view of a part of the book in Figure 1, the top cover being open.

Figure 3 is a detail perspective view of a portion of the lower cover showing one of the posts.

Figure 4 is a cross section taken on the line 4—4 of Figure 1.

Figure 5 is a detail perspective view of a part of one of the angular cover plates.

Figure 6 is an enlarged sectional view of the bottom cover plate.

Figure 7 is a perspective view of a modified form of the invention.

Figure 8 is a cross section taken on the line 8—8 of Figure 7.

Figure 9 is a perspective view of a portion of another modified form of the invention.

Figure 10 is a detail section taken on the line 10—10 of Figure 9.

Attention is first directed to the first form of the bookbinding in Figures 1 to 6 according to which the binding has a sewed book appearance. This, like the other two forms of the invention, has top and bottom covers 1, 2. These are spaced apart and contain a quantity of leaves 3 between them. The buckram or other covering material 4 is so brought together at 5 as to produce a hinge, and it is on this hinge that the top and bottom covers are swingable when required.

Immediately beyond the hinge points there are angular top and bottom cover plates 6, 7 of light-weight metal such as galvanized iron, constituting leaf-confining members. Each of these is identical and of the form in Figure 5. It comprises a fold-over flange 8 and a plain flange 9. These flanges are at right angles to each other. The folded over flange contains reinforcing means 10 providing the necessary strength and stiffness, 45 against which the compression means is compressibly secured. The folded over flange has a plurality (at least two) of holes 11 to admit the compression means.

So far it will be understood that each cover has a metallic cover plate attached to it at its hinge point. In the assembled book the folded over flange 8 bears down on the leaves 3 above and below (Fig. 4). The plain flange 9 partially conceals the back edges of the leaves adjacent 55

to the top and bottom. The covering 4 is carried down over the outside of the respective cover plates 6, 7, so that all have a finished appearance.

Provision is made of compression means for securing the tubular posts to the top and bottom covers. The compression means consists of screw nails 12 and 120. Those screw nails 120 which are driven into the upper ends of the posts are threaded all the way (Fig. 4). The screw nails 10 can consist of any edge-formed type of shank. The bite that the illustrated spiral thread affords is equally well obtainable by one or more straight edges on the nail shank. Those (12) that are driven into the lower ends of the posts are 15 threaded part way, being shouldered at 12^a and continuing on as smooth shanks 12^b to the heads of the nails. A number of tubular posts are initially made up by partially driving a shouldered screw nail into one end of each leaving a 20 portion of the screw thread exposed. This is done by hammering on the heads 14. The heads of the top screw nails are similarly designated. Upon initially starting the book some of these posts are inserted in the holes 11 of the bottom 25 plate 7.

In order to fix the tubular posts to the bottom cover plate at this stage, clinchers constituting concave washers 15 are slipped down over the posts. The outside diameter of each post and of the shank 12^b is the same. The clincher, therefore, slips as easily onto the shank as it does along the post. The head 14 of each post is then placed on an anvil, and a special tool is used to set the clincher. Originally the convexity 30 of the clincher faces upwards (Fig. 3). The act of setting concaves the top of the clincher as at 15^a (Fig. 6), causing an edge of the clincher hole to bite the shank 12^b. The setting act compresses the bottom cover plate 7 at the tubular 35 post places to some degree (Fig. 6) and establishes a rigid connection of the posts to the bottom cover plate which it is impossible to separate under ordinary working conditions.

One half of the desired number of leaves 3 40 to be bound in the binder are emplaced upon the tubular posts 13 in the bottom cover 2, whereupon the fins 20 of the independent back 18 are slipped over the posts, followed by the other half of the leaves. The top cover 1 is then 45 fitted on. The posts 13 go through the holes 11 in the top cover plate 6, the cover 1 obviously being in the open position. The projecting parts of the posts are cut off, preferably by crimping with pliers and then bending until they snap, the cut being substantially flush with the top 50 of the cover plate 6, preferably leaving about $\frac{1}{8}$ " of the post standing above the top cover. The top screw nails 12 are then driven into the cut off ends of the posts, which action rounds out 55 the respective hollow post and permits it to go down into the cover plate, until the head of the screw nail rests on the top cover plates. When driving these screw nails in, the screw nail heads 14 in the bottom cover are again placed on the anvil. The act of hammering upon the top heads not only drives the top nails in but drives the respective tubular post down upon the bottom nails until the bottom ends of the posts meet 60 the shoulders 12^a (Fig. 6) thus completing an adjustment at each of the two leaf-confining members 1, 2. The threads of the bottom nails, which were exposed up to this time, are thus covered, and the distance represented by the 65 final movement of the posts over the exposed 70 75

expanses of the bottom nails constitutes what has previously been called the floating action.

It is the provision of this action which makes it possible to finally compress the leaves very tightly along the binding edge. Figure 4 shows particularly well how the heads 14 of the top and bottom nails conceal the ends of the respective tubular posts. The lower end of the post is some distance from the lower head 14, and even though the upper end of the post is directly adjacent to the upper head 14, that head extends out over the end of the post which has been rounded out and driven down on the compression means in the bottom cover.

Recesses 16 in the top and bottom covers 1, 2 receive the cover plates 6, 7 when the book is closed. Although the heads 14 are partially buried in the buckram they protrude a little nevertheless, but the recesses 16 are deep enough to accommodate the nail heads and the cover plates. 20 These recesses are produced in forming the covers, and the hinge lines 5 run along the outer parts of the recesses.

Mention was made of the posts 13 protruding above the top cover plate 6 preparatory to completing the binding. Ordinarily 6" tubular posts are provided. Such a length is suitable for any sheet capacity from 1" up to 5½". Longer posts up to 12" may be used if a capacity greater than 5" is required. Having selected the proper length of tubular post a shouldered screw nail is driven through the fold-over flange 8 into the bottom end of the post, whereupon the procedure already outlined is followed. When the binding is completed the nail heads 14 bear on the remote sides of the folded over flanges 8, the heads having sufficient bearing thereon to prevent the flanges from ever pulling away.

Now revert to Figure 4. An independent back 40 18 is secured in the combination. This consists of a single piece of metal 19 so folded upon itself as to provide duplex center fins 20. These have holes through which the posts 13 are inserted, and in practice the center fins are so thin that they do not produce any objectionable space in 45 the pile of pages. The independent back has reinforcing means 21 which gives it body, and the back has a covering 22 of buckram or the like, matching the covering 4.

The independent back overlaps the plain flanges 50 of the top and bottom cover plates 6, 7. This overlap allows for considerable expansion. The plates 6, 7 and the back 18 provide what is herein known as a three-piece back which automatically provides a covering for a variable quantity of 55 sheets. It is plain in Figure 4 that quite a number of additional sheets could have been inserted, still maintaining the overlapping relationship of the back and the plain flanges 9.

Attention is next directed to Figure 7. This 60 has fold-over top and bottom angle plates 6^a, 7^a with fold-over flanges 8^a and plain flanges 9^a (Fig. 8). The screw nails 12 are identical in every respect to those depicted in Figure 4, the same reference characters being used for the parts. The tubular posts 13^a as well as the bottom clinchers 15^a and all structure immediately concerned with the connecting means (consisting of the screw nails and tubular posts in all cases) are the same as previously described. One 65 exception is that the top and bottom covers 1^a, 2^a are connected to the forward edges of the angle plates. Consequently the heads 14 of the screw nails are exposed on the outsides of the top and bottom cover plates.

The independent back 18^a is made of flexible material such as cardboard covered with cloth, and is not rigid as in the preceding form. It is covered with the same material used on top 5 and bottom covers, and its lateral edges 23 are inserted beneath the plain angle flanges 9^a as shown. This arrangement provides an overlap similar to that previously described and the overlap provides for considerable expansion. As 10 plainly seen in Figure 8 the back of the book is of three-piece construction, this comprising the top and bottom cover plates and the flexible backing 18^a.

A carrying strap 24, or equivalent carrying 15 means is attached to the flexible back by means of an appropriate clip 25 which goes through holes 26 in the flexible back, between the leaves of the book and around the adjacent tubular post 13^a as denoted at 27 (Fig. 8). The carrying 20 strap, especially its clip 25, serves to hold the flexible back 18^a in position beneath the angle flanges 9^a.

Figures 9 and 10 illustrate the third form of the invention. The back, whether rigid as in 25 Figure 1 or flexible as in Figure 7, is now omitted, the back edges of the leaves being exposed. The covers 1^b, 2^b have folded over top and bottom binding plates 28, each of the form shown in Figure 10. The fold contains reinforcing means 30 29. The screw nails 12 are driven into the ends of the tubular posts 13^b the same as before, the heads 14 and the clinchers 15^a serving to make a tight binding around the plates 28. The heads of the screw nails are exposed on the outside 35 as in the preceding form but the ends of the tubular posts are concealed.

The fact that the tubular posts are permanently held at one end makes it possible to temporarily use the binder as a current binder particularly the forms in Figures 7 and 9. There the top covers have holes through which the tubular posts may protrude, the top cover being slid down to temporarily hold the leaves. When it is finally desired to bind the leaves that part of 45 the post which extends above the top cover is cut off as already described, and the top cover is riveted down to complete the book.

As regards the top and bottom cover plates 6, 7, 6^a, 7^a and 28, the reinforcing means contained therein is considered very essential as it prevents the head of the screw nail from pulling through from the outside. These plates also provide a metal base for the clincher which otherwise would not hold on the inside. The reinforcement in the fold provides the necessary thickness so as to properly match the thickness of the covers themselves. The reinforcing means should consist of steel or other metal for current use and of binder's board for permanent use. 50 Binder's board is compressible (Fig. 6) and enables making a very tight connection when the screw nails are driven home.

Further, these top and bottom plates are preferably made of galvanized iron. It has been 55 found that binding materials, for example the buckram cover 4 will firmly stick to a galvanized surface, whereas an ordinary steel plate surface must first be treated, which requires additional labor and material.

70 I claim:—

1. In a binder, spaced leaf-confining members having registering openings, at least one tubular post spanning the space between said members in registration with the openings, means secured to one of the members in one of the open- 75

ings and partially driven into one end of the post to initially adjustably attach the post to one of the members and to carry it in a temporary loose position during the emplacing of leaves on the post and building up a book, and similar means adapted to be driven through the other opening into the other end of the post after severing said post above the top leaf-confining member thereby to completely drive in the first means and fixedly attach to it the respective member. 10

2. In a binder, spaced leaf-confining members having registering openings, at least one tubular post spanning the space between said members and adapted to line up with the openings, means occupying one of the openings and driven partially into one end of the post to adjustably connect the post and hold it in a floating position while emplacing leaves up to book size, similar means inserted through the other opening and driven into the other end of the post after severing said post above the top leaf-confining member, the axial thrust of the blows driving the first means in farther and causing both means to tightly attach the members to the substantial ends of the post, and clincher means interposed between one of said members and the adjacent end of the post gripping the inserted means to rigidly hold the post. 15 20 25

3. In a binder, separated binder members providing covers for a quantity of leaves, said members having confronting openings, a tubular post spanning the distance between said members and lining up with the openings, one end of the post being spaced from the respective binder member the opposite end of the post occupying the opening in the other binder member, a headed element driven through each opening into the respective end of the tubular post to secure the post to said members, each element having an 30 35 edge-formed body, the edges of which are forced into the walls of said post, one element having a shoulder which is abutted by said one end of the post at said space, and clincher means gripping said one element adjacent to the shoulder at 40 45 a place between the end of the post and adjacent binder member.

4. In a binder, spaced leaf-confining means including cover plates having folded over flanges and plain flanges at angles to each other, the plain flanges being directed toward each other, compressible reinforcing means between the folded over flanges, connecting means connecting said members and retaining a quantity of leaves, and compression means driven through 50 55 said folded over flanges into the connecting means, said reinforcing means being partially compressed.

5. In a binder, spaced leaf-confining members, leaf-retaining means and means by which it is secured to said confining members, a back, a carrying strap, and means securing the carrying strap both to the back and to one of the leaf-retaining means. 60

6. In a binder, spaced leaf-confining members, leaf-retaining means and means by which it is secured to said confining members, a back, a carrying strap, and a clip going through holes in the back and being secured to one of the leaf-retaining means, thereby securing the strap both 65 70 to the back and to said leaf-retaining means.

7. In a binder, spaced leaf-confining means including cover plates having folded over flanges and plain flanges at angles to each other, the plain flanges being directed toward each other, 75

compressible reinforcing means between the folded over flanges, connecting means to connect said members and retain a quantity of leaves, compression means driven through said folded over flanges into the connecting means, said reinforcing means being partially com-

pressed, and covers, each having means providing a single hinge attached to the respective plain flange, the covers having recesses adjacent to the hinges to contain the folded over flanges when the binder is closed.

FRANK H. CRUMP.
